United States Patent

Des. 236,692
Patented Sept. 9, 1975

236,692

COVERED COMPARTMENTED FOOD TRAY

Donald Andrew Haase, Penfield, N.Y., assignor to Mobil
Oil Corporation, New York, N.Y.

Filed Mar. 16, 1973, Ser. No. 342,240

Term of patent 14 years

Int. Cl. D9—03

U.S. Cl. D9—185

FIG. 1

FIG. 2

FIG. 1 is a perspective view of a covered compartmented food tray showing my new design in a partially opened condition;

FIG. 2 is a bottom plan view thereof in a fully opened condition;

FIG. 3 is a top plan view thereof;

FIG. 4 is a cross-sectional view thereof taken along line 4-4 of FIG. 3;

FIG. 5 is a left side elevational view shown in a closed condition; and

FIG. 6 is a front elevational view of FIG. 5.

I claim:

The ornamental design for a covered compartmented food tray, substantially as shown and described.
